SUCTION CUP

Frederick Charles Brewer and Frederick William Johonet, Los Angeles, Calif., assignors to Foot-sure Company, Incorporated, Los Angeles, Calif., a corporation of California

Application July 14, 1936, Serial No. 90,515

6 Claims. (Cl. 4—185)

This invention relates to suction cups of the class adapted to support attached articles against lateral displacement on either horizontal or vertical smooth exteriors such as glass, tile, or 5 enameled metal.

Resilience in the composition of suction cups is of the greatest importance to create a pressure differential between the chamber therein and the area therearound, and also to enable the 10 greater outside pressure to initially mold the surface contacting lips of the cup, with minimum resistance to conformance with the shape of the surface upon which it is intended to engage. However, the effectiveness of suction cups of the 15 prior art, while depending to a large extent upon the size and acuity of their frictional contacts, is often reduced by the flexing of the cup in response to strains thereon, which tends to distort the normal contour of the dome, causing creases 20 in the contacting edges through which outside pressure may be admitted. Accordingly, to combine maximum rigidity when in operating position with utmost resilience of the contacting lips and collapsible dome in suction cups embodying 25 vacuum chambers of any size commensurate with specific requirements, is a general object of this invention.

It is a particular object to provide a resilient vacuum cup adapted for use principally in bath 30 mats, having auxiliary surface engaging lips in the center of the dome to minimize tendency towards displacement by lateral stress.

Another object of our invention is to provide a suction cup having a series of concentric vacuum chambers of different sizes in which the 35 contacting lips, bounding the innermost suction chamber, are adapted to reinforce the outer annular chamber against lateral displacement.

Another object is the provision of a mat utilizing the pressure differential created between the suction chamber and the external or atmospheric pressure to maintain its grip, adapted to adhere with equal tenacity to an immersed, 40 damp, or dry surface, but which may be removed 5 with ease.

Another object is to provide a bath mat having a plurality of vacuum cups embodying the characteristics above indicated, having the lower ends 45 of their annular lips terminating above the base of a series of equi-spaced, V-shaped wales carried by the underside of the body of the mat between the cups, to permit lowering of the 50 lips to surface-engaging position upon expulsion of fluid from the suction chambers.

Other objects such as efficiency and facility of

operation, economy of manufacture, and simplicity of construction will be apparent to those of skill in the art to which this invention appertains upon an examination of the following description read in the light of the accompanying drawing, in which—

Fig. 1 is a perspective view of a small portion of a bath mat embodying our invention, showing its upper surface;

Fig. 2 is a plan view of the underside of the 10 mat illustrated in Fig. 1, partially broken away;

Fig. 3 is a sectional view taken on lines 3—3 of Fig. 1.

Referring to the drawing in detail, the numerals of which indicate similar parts throughout the several views, 5 designates the body of a bath mat composed of any material embodying resilience and strength. The upper face of the mat is molded with any distinctive design such as exemplified by the cross ribs 6. The underside of the mat is covered longitudinally by a series of spaced, parallel wales 7, V-shaped in cross section, forming channels 8 therebetween through which fluid trapped below the mat may escape. This feature obviates the disadvantage common to prior art bath mats failing to provide exit means for the fluid, which results in the mat floating or gliding laterally on a wet shower or tile floor by the sudden application of weight. The flexibility of the mat permits the sharp 30 edges of the wales to enter the slightest concavity in the surface which it contacts and engage the edges thereof.

Vacuum cups, indicated generally by the numeral 9, are molded integrally with the mat, preferably in spaced relation. One of such cups is described below, it being understood that the number, spacing, or addition of conventional features, is within the scope of this invention. A dome 10, of a thickness most adaptable to the 40 material utilized to provide a maximum resiliency, is formed in the body 5 with its convex side extending slightly above the upper surface of the mat. In the inside of the dome 10 and substantially at its center, a downwardly protruding stud 11 is molded. The length of stud 11 is preferably less than the distance between the underside of the dome and the horizontal plane through the base of wales 7, so as to normally be out of engagement with the surface 50 supporting the wales. The stud 11 may be hollow or its lower end concave, as indicated at 12, forming an auxiliary suction cup which will engage the surface upon which the wales are in contact by the application of pressure on the dome.

A circular channel 13 is molded in the underside of the body of the mat below and slightly outside of the periphery of the dome. Between the vacuum chamber formed in the annular area 5 of dome 10 around stud 11 and channel 13 a circular rim 14 is provided, extending downwardly and terminating in a plane intermediate the base of the wales and the lower end of stud 11.

It will be seen that the lower edges of stud 10 11 and rim 14 normally are supported above the surface on which the mat is laid, by the wales 1 and the body of the mat. The collapse of the dome 10 either by stepping upon the mat or manually, where convenient, forces the fluid 15 from the suction chambers and utilizes outside pressure to urge the rim and lower edges of the stud into engagement with the surface. In cups having the edge of the dome normally in contact with the surface, the resistance of the cup 20 to lateral displacement depends entirely upon the resilience of the dome. In the present invention, however, the channel 13 is normally in communication with the suction chamber beneath the dome, and the bridge 15 overhanging the 25 channel is depressed with the dome, the resilience of which is combined to create the pressure differential. In effect, our invention provides a vacuum chamber equal in diameter to the outside boundary of the channel 13 in which 30 a series of concentric circular contacting lips are embodied to engage the surface, and thereby resist displacement as well as to lend strength in the elements thereof to avoid the admission of air through creases formed by lateral strain on 35 the cup.

While we have described the suction cups of our invention for use particularly in conjunction with bath mats, it should be understood that the cups may be utilized singly or in groups to 40 support various other articles in an obvious manner, incidental alterations in the method and means of attachment thereto being within the ability of those of skill in the art. Numerous changes in size, proportion, arrangement, and 45 design of both mat and the suction cups, individually and relative to each other, may be made without departing from the essence of our invention as defined in the appended claims.

What we claim and desire to secure by Letters 50 Patent is:

1. In a device of the character described, a

bath mat having formed in one of its surfaces a series of spaced, parallel wales, a vacuum cup formed in said surface comprising a dome having its convex surface extending slightly above the opposite surface of the mat, a circular channel formed in the mat around the concave of the dome, said channel and dome being separated by a rim having its lower periphery terminating above a plane through the base of said wales, and a stud substantially in the center of the 10 concave of said dome having its lower end concave to form a suction chamber.

2. In a device of the character described, a body having a concavo-convex resilient suction cup therein, a channel surrounding said cup, and 15 a stud in said cup having its lower end concave.

3. In a device of the character described, a resilient dome-shaped body, a stud carried by the concave surface of said body having a hollow lower bore, and a circular rim extending downwardly from the concave surface of said body, having its lower end terminating in a plane intermediate the lower end of the stud and the outside edge of said body.

4. In a device of the character described, a 25 resilient body having a concavo-convex dome, said dome having surface-engaging edges, an endless rim extending downwardly from said dome between said edges, and an auxiliary vacuum cup within and forming an integral part of 30 said dome.

5. In a device of the character described, a resilient body having a surface-engaging lip, a resilient dome in said body adjacent said lip, a resilient stud extending downwardly from and 35 secured to the concave side of said dome, having its free end terminating above said lip to flex upon abutment against the surface to be engaged by pressure on said dome, said stud being adapted by its resiliency to urge said dome 40 to its original position upon release of pressure thereon, the lower end of said stud being concave.

6. In a device of the character described, a body having a surface-engaging endless lip, a 45 resilient dome within said lip, a resilient bridge connecting said dome with said body, and an auxiliary suction cup extending downwardly from and connected to said dome.
